United States Patent

Des. 238,299

Patented Dec. 30, 1975

238,299

HEATED CABINET

Richard O. Klemm, Crystal Lake, Ill., assignor to Food Warming Equipment Company, Inc., Elk Grove Village, Ill.

Filed Apr. 8, 1974, Ser. No. 459,088

Term of patent 14 years

Int. Cl. D12—02; D15—08
U.S. Cl. D55—1 E

FIG. 1 is a left front perspective view of a heated cabinet showing my new design;

FIG. 2 is a front elevation view thereof;

FIG. 3 is a rear elevation view thereof;

FIG. 4 is a top plan view thereof;

FIG. 5 is a left side elevation view thereof; and

FIG. 6 is a bottom plan view thereof.

The right side of the heated cabinet is substantially flat and unornamented.

I claim:

The ornamental design for a heated cabinet, substantially as shown and described.
